LADDER BRACKET

Harold G. Sloss, Ellwood City, Pa.

Application July 7, 1947, Serial No. 759,427

2 Claims. (Cl. 228—60)

1

This invention concerns a ladder bracket and clamp for holding a scaffolding ladder in upright position adjacent the wall of a building.

It is a major object of the invention to provide a ladder bracket and clamp which may be attached to the side of the building and will support itself in proper position while a scaffolding ladder is raised or lowered to its proper place.

Another object of the invention is to provide a self-supporting ladder bracket which may be folded flatly for purposes of handling and storage.

A further object of the invention is to provide a ladder bracket and clamp which is capable of holding a ladder on either side of its ladder supporting arm.

A still further object of the invention is to provide an improved ladder bracket which is of simple construction and may, therefore, be economically fabricated from standard materials.

Other objects and advantages of the invention will become apparent from the following specification taken in connection with the accompanying drawing, wherein:

Figure 1 is a perspective view of a ladder clamping bracket embodying the invention and shown positioned on the wall of a building and holding a ladder;

Figure 2 is a top plan view of the ladder bracket shown in Figure 1;

Figure 3 is a side elevation, with the clamping member removed, of the ladder bracket shown in Figure 1;

Figure 4 is a front elevation, with the clamping member removed;

Figure 5 is a front elevation showing the ladder bracket in folded position, the clamping member being removed for purposes of clearness, and

Figure 6 is a top plan view of the ladder bracket in folded position.

According to the invention in its preferred form, the ladder bracket has a wall engaging fixture provided with a pair of mutually perpendicular arms which carry a ladder supporting arm extended outwardly from the fixture. The ladder supporting arm may be pivoted to the fixture so it can be folded flush therewith during transportation and storage. The ladder supporting arm is provided with an elongated slot through which extend threaded end portions of a U-shaped clamp. With the fixture attached to the wall of a building and the ladder supporting arm extending outwardly, a scaffolding ladder may be raised or lowered between the clamp and the ladder supporting arm until it is prop-

2

erly positioned. By tightening the clamp, the ladder is secured and retained in proper position with respect to the wall.

Referring now to the embodiment of the invention shown in the accompanying drawings, a wall engaging fixture designated generally at 11 is provided with mutually perpendicular arms 12 and 13 formed of angle iron. The arm 12, referred to as the wall engaging arm, has a pair of projections 14 and 15 extending upwardly therefrom. Each of these projections is provided with a bayonet slot 16 for securing the fixture on screws or nails 17 embedded in the wall of the building. For purposes of rigidity, a brace 18 may be arranged between the two arms 12 and 13 and have its ends secured to them respectively.

A ladder supporting arm designated generally at 19 is formed of strap material having one end 20 pivotally connected as by rivet 21 to the horizontal flange of the angle iron forming wall attaching arm 12. The strap iron of the ladder supporting arm 19 is folded upon itself at 22, and the other end is secured to the fixture 11.

In the drawing, this other end is shown as being secured to a shelf 23 on one flange of the angle iron forming steady arm 13. The strap material is pivotally secured to the shelf 23 as by rivet 24. Preferably, at a point spaced from the fixture 11, the folded portions of the strap material are secured together as by rivet 25. Also, the underneath folded portion of the arm 19 extends from the rivet 25 downwardly to form a brace 26, the end of which is secured by the rivet 24 to shelf 23.

In order to permit the ladder supporting arm 19 to be folded flush with the fixture 11, the rivets 21 and 24 may be loosely fitted so the entire ladder supporting arm may turn about an axis parallel to the steady arm 13. To hold a ladder in position, a U-shaped clamp 27 has its end portions 28 and 29 extending through the elongated slot 20 between the upper and lower strap portions of arm 19. The U-shaped clamp 27 is shaped to surround the ladder and has threaded ends 31 and 32 provided with wing nuts 33 and 34, which engage the sides of the strap member 19 to retain the clamp 27 and tighten the clamp on the ladder. To maintain the formation of the elongated slot 27, a spacer 35 may be positioned between the folded portions of the strap material and intermediate the ends of ladder supporting arm 19. This spacer 35 also serves to prevent the member 27 from sliding out of the slot when it is not supporting a ladder.

Sometimes it is desired to hold a ladder on each side of the ladder supporting arm. In other cases, it is desirable to have an option as to which side of the ladder supporting arm a ladder will be placed. To take care of such contingencies, a second U-shaped clamp 37 has one end portion 38 extending through the slot 20 and its other end 39 extending through a slot 41 formed by a strap member 42 secured beneath the upper folded portion of the strap forming the ladder supporting arm 19 adjacent the fixture 11. Rivets 43 and 44 may hold the strap member 42 in position.

In order to retain the ladder supporting arm 19 in position perpendicular to the arms 12 and 13, a detachable brace 46 has one end pivoted as by the rivet 25 to the ladder supporting arm 19. Its other end may be secured to the upper flange of wall engaging arm 12 as by a bolt 47 and a wing nut 48. In order to fold the ladder supporting arm 19, the wing nut 48 is removed, the bolt 47 withdrawn, and the arm 46 swung to a position coincident with the ladder supporting arm 19. The ladder supporting arm may then be turned about its pivots 21 and 24 to a position flush with the fixture 11 as shown in Figures 5 and 6.

In erecting a scaffold, the ladder bracket is attached to a wall by suitable devices such as bayonet slots 16 and bolts 17. The ladder supporting arm 19 may then be secured in position by connecting the brace 46 to the wall attaching arm 12 as by the bolt 47 and wing nut 48. A ladder is then raised to the desired position on either side of the ladder supporting arm 19, and the wing nuts on the ladder clamp 27 or 37 are tightened to clamp and hold the ladder between the clamp and the ladder supporting arm. To remove the ladder, the wing nuts on the clamp are loosened, the ladder lowered, and the fixture readily removed from the wall by sliding the bayonet slots 16 over the heads of bolts 17. If desired, the ladder supporting arm 19 may then be folded flush with the fixture 11 to form a flat package for purposes of handling and storage.

What I claim is:

1. A ladder bracket comprising a building wall engaging fixture having a horizontal arm for attachment to the building wall and a steadyng arm depending vertically from said horizontal arm, a ladder supporting arm extending outwardly from said fixture and having one end attached to the juncture of said horizontal arm and said steadyng arm, a vertical brace connected between an intermediate point on said ladder supporting arm and a point on said steadyng arm below the juncture of said arms, a horizontal brace connected between an intermediate point on said supporting arm and a point on said horizontal arm spaced from the juncture of said arms, said ladder supporting arm having upper and lower portions forming a longitudinal slot

extending horizontally between its sides, a substantially U-shaped clamp having its free ends disposed in said slot, said clamp and said ladder supporting arm being shaped and arranged to embrace a ladder, and means on the free ends of said clamp for tightening the clamp against the ladder.

2. A ladder bracket comprising a building wall engaging fixture having a horizontal arm for attachment to the building wall and a steadyng arm depending vertically from said horizontal arm, a ladder supporting arm having one end pivoted to said fixture at the juncture of said horizontal arm and said steadyng arm to turn about a vertical axis, a brace having one end attached to said ladder supporting arm at a point spaced from its pivotal connection to said fixture and having its other end pivoted on said steadyng arm at a point spaced downwardly from the juncture of said arm so said brace may turn about the same axis as said ladder supporting arm, a detachable brace having one end connected to said ladder supporting arm at a point spaced from its pivotal connection to said fixture and having its other end connected to said horizontal arm at a point spaced from the juncture of said arms, said detachable brace being arranged to retain said ladder supporting arm horizontally positioned substantially normal to said fixture and extending outwardly from the building wall, one end of said detachable brace being disconnectable to permit said ladder supporting arm to be turned about the axis of said pivots to a folded position in the plane of said fixture, said ladder supporting arm having spaced upper and lower portions forming a longitudinal slot extending horizontally between its sides, a substantially U-shaped clamp having its free ends disposed in said slot, said clamp and said ladder supporting arm being shaped and arranged to embrace a ladder, and means on the free ends of said clamp for tightening the clamp against the ladder.
